UNITED STATES PATENT OFFICE.

CHARLES S. BOCK, OF CHICAGO, ILLINOIS, ASSIGNOR TO ANDREW HOFFMAN MFG. CO.,
OF CHICAGO, ILLINOIS, A CORPORATION OF ILLINOIS.

METAL CASEMENT WINDOW.

Application filed February 20, 1924. Serial No. 693,961.

To all whom it may concern:

Be it known that I, CHARLES S. BOCK, a citizen of the United States, residing at Chicago, in the county of Cook and State of Illinois, have invented certain new and useful Improvements in Metal Casement Windows, of which the following is a specification.

The principal object of the invention is 10 to provide a metal casement window wherein the main structural components of the fabrication constitute metal bars of standard shape.

The window of the invention is particularly characterized by an attractive appearance which is equally suited for residential or commercial installations; a light but durable construction which is in conformity with the diverse specifications of heavy or 20 light service; and a relatively low production cost which is attainable in either large or small quantity production owing to the availability of the standard bars and the simple formative operations involved in 25 cutting, fitting, and joining the bars.

Other objects and advantages which are not specifically referred to in this disclosure will be appreciated upon a full comprehension 30 of the construction of the window and the arrangement therein of the standard bars.

For the purpose of exemplification, a preferred embodiment of the invention is presented in the accompanying drawing and in 35 the following detailed description. Inasmuch, however, as other slightly modified structural embodiments would also come within the purview of the invention, the particular embodiment here presented is not 40 to be considered as limiting the spirit of the invention short of its intended scope as defined by the appended claims.

In the drawing—

Fig. 1 is a front elevation of a double 45 casement window which is constructed in accordance with the invention;

Fig. 2 is a horizontal section on the line 2—2 of Fig. 1;

Fig. 3 is a vertical section on the line 50 3—3 of Fig. 1; and

Figs. 4 and 5 are fragmentary horizontal sections taken respectively through the abutting stiles and through one side stile and jamb of a metal casement window wherein 55 are embodied special metal bars which have

the over-all sectional configuration of the standard metal bars of the invention.

It will be observed in the drawing that the window includes a frame 10 and two articulated sash portions 11 and 12. The 60 invention resides, primarily, in the novel construction of the frame and the sash portions, and, secondarily, in certain improved features in the mounting arrangement of the frame and the sash portions. The general 65 mounting arrangement of the frame and the sash portions is, however, a separate invention which is covered in my copending application, Serial No. 675,992, filed November 21, 1923.

The frame 10 is a fabrication wherein the lintel, the sill and the jambs severally comprise two standard metal angle bars 13 13 which are so positioned in oppositely lapped relation as to present an outwardly 70 extending flange 14 in the front plane of the frame and an inwardly extending flange 15 in the rear plane of the frame. The contacting side portions of the bars are welded at 16 to each other, and the end portions of 75 the bars are welded at 17 to the end portions of the bars of each adjoining side of the frame.

The sash portions 11 and 12 are fabrications wherein the abutting stiles severally 80 comprise a standard metal channel bar 18 which is so positioned as to present outwardly extending flanges 19 and 20 in the front and rear planes of the sash portions and wherein the rails and the side stiles 90 severally comprise a standard metal angle bar 21 which is so positioned as to present an outwardly extending flange in the front plane of the sash portions and a rearwardly 95 extending flange 23 perpendicular to the front plane of the sash portions at the inner margin of the outwardly extending flange 22. The front outwardly extending flange 19 of the sash portion 11 is provided with a strip 24 which laps against the front face 100 of the corresponding flange of the sash portion 12, and the rear outwardly extending flange 20 of the sash portion 12 is provided with a strip 25 which laps against the front face of the corresponding flange of the sash portion 11.

The end portions of the bars of each sash portion are welded at 26 to each other. The muntins of each sash portion comprise standard metal T bars 27 and the glazing supports along the sides 110

of each sash portion in opposition to the muntins comprise standard metal angle bars 28.

When the two sash portions are made to assume the closed position illustrated, the flanges 19 and 20 of one sash portion abut against the corresponding flanges of the other sash portion, the flanges 22 of the two sash portions lap snugly against the flanges 14 of the frame, and the flanges 21 of the two sash portions abut snugly against the flanges 12 of the frame; thereby providing a double line of contact and a resulting air pocket between the two sash portions and between each sash portion and the frame.

The general mounting arrangement of the frame and the sash portions consists in connecting the abutting stiles of the sash portions to each other by means of hinges 29 at the rear face of the sash portions and in pivotally mounting the spaced side stiles of the sash portions to vertically extending fixtures 30 by means of hinges 31, which fixtures are in turn mounted for horizontal sliding movement in the frame toward and away from the jambs of the same. As previously stated, such general mounting arrangement is covered in my copending application, but an improved structural feature of the arrangement which is peculiarly adapted to the present window construction consists in the provision, at each of the hinges 31, of a shallow notch 32 in the outer margin of the flange 22 through which notch 35 the hinge leaf which engages with the fixture passes rearwardly, whereby to provide by such disposition of the hinge leaf, an unbroken contour for each sash portion and a weather-proof closure at each hinge.

It will be appreciated, from the foregoing description that the window of the invention is susceptible of a wide range of use and may be produced in any desired quantity at a very low cost, since the metal bars used in the fabrication are always obtainable, and no special skill is required in cutting, fitting and joining the bars.

In Figs. 4 and 5 is illustrated a window which, unlike the window of the invention, embodies special metal bars in its construction. The over-all sectional configurations of the special bars correspond, however to those of the standard bars embodied in the present invention.

I claim:

1. A double casement sash of metal construction, wherein the abutting stiles severally comprise a standard metal channel bar which is so positioned in the fabrication as to present outwardly extending flanges in the front and rear planes of either sash portion for abutment against the outwardly extending flanges of the complementary sash portion, and wherein one of the outwardly extending flanges of each sash por-

tion is provided with a strip which laps against the corresponding flange of the other sash portion.

2. A double casement sash of metal construction, wherein the abutting stiles severally comprise a standard metal channel bar which is so positioned in the fabrication as to present outwardly extending flanges in the front and rear planes of either sash portion for abutment against the outwardly extending flanges of the complementary sash portion, and wherein the rails and the side stiles severally comprise a standard metal angle bar which is so positioned in the fabrication as to present an outwardly extending flange in the front plane of either sash portion and a rearwardly extending flange perpendicular to the front plane of either sash portion at the inner margin of the outwardly extending flange. 85

3. A casement sash frame of metal construction, wherein the jambs severally comprise two standard metal angle bars which are so positioned in the fabrication in oppositely lapped relation as to present an outwardly extending flange in the front plane of the frame and an inwardly extending flange in the rear plane of the frame. 90

4. A casement sash frame of metal construction, wherein the lintel, the sill and the jambs severally comprise two standard metal angle bars which are so positioned in the fabrication in oppositely lapped relation as to present an outwardly extending flange in the front plane of the frame and an inwardly extending flange in the rear plane of the frame. 95

5. A casement sash frame of metal construction, wherein the lintel, the sill and the jambs severally comprise two standard metal angle bars which are so positioned in the fabrication in oppositely lapped relation as to present an outwardly extending flange in the front plane of the frame and an inwardly extending flange in the rear plane of the frame; and a casement sash of metal construction for the frame, wherein the rails and the stiles severally comprise a standard angle bar which is so positioned in the fabrication as to present an outwardly extending flange in the front plane of the sash and a rearwardly extending flange perpendicular to the front plane of the sash at the inner margin of the outwardly extending flange. 110

6. A casement sash frame of metal construction, wherein the lintel, the sill and the jambs severally comprise two standard metal angle bars which are so positioned in the fabrication in oppositely lapped relation as to present an outwardly extending flange in the front plane of the frame and an inwardly extending flange in the rear plane of the frame; and a double casement sash of metal construction for the frame, wherein the 115

abutting stiles severally comprise a standard metal channel bar which is so positioned in the fabrication as to present outwardly extending flanges in the front and rear planes of either sash portion for abutment against the outwardly extending flanges of the complementary sash portion, and wherein the rails and the side stiles severally comprise a standard metal angle bar which is so positioned in the fabrication as to present an outwardly extending flange in the front plane of either sash portion and a rearwardly extending flange perpendicular to the front plane of the sash at the inner margin of the outwardly extending flange.

7. A casement sash of metal construction, wherein the stiles severally comprise a standard angle bar which is so positioned in the fabrication as to present an outwardly extending flange in the front plane of the sash and a rearwardly extending flange perpendicular to the front plane of the sash at the inner margin of the outwardly extending flange; and supporting fixtures for the sash, including hinge leaves positioned on the outwardly extending flanges of the stiles with the hinge butts set inwardly from the outer margins of the flanges, and other coacting hinge leaves extending rearwardly from the hinge butts through notches cut in the outer margins of the flanges.

8. A casement sash of metal construction, wherein the stiles severally comprise a standard angle bar which is so positioned in the fabrication as to present an outwardly extending flange in the front plane of the sash and a rearwardly extending flange perpendicular to the front plane of the sash at the inner margin of the outwardly extending flange; and supporting fixtures for the sash, including hinge leaves positioned on the outwardly extending flanges of the stiles with the hinge butts set inwardly from the outer margins of the flanges, and other coacting hinge leaves extending rearwardly from the hinge butts through notches cut in the outer margins of the flanges.

9. A casement sash frame; a double casement sash wherein the abutting stiles are hinged to each other at the rear face of the sash; and means for supporting the side stiles of the sash relative to the frame, comprising two vertically extending hangers, guides in the lintel and sill of the frame to permit horizontal sliding movement of the hangers in the frame, and a plurality of hinges having corresponding leaves secured to the side stiles and other corresponding leaves secured to the hangers.

In testimony whereof I have hereunto signed my name.

CHARLES S. BOCK.
